WITNESSES.

INVENTOR.

UNITED STATES PATENT OFFICE.

FREDERIC L. FELTON, OF BOSTON, MASSACHUSETTS.

DESIGN FOR COMBINED CALENDAR AND PAPER-WEIGHT.

SPECIFICATION forming part of Design No. 11,937, dated August 10, 1880.

Application filed March 8, 1880. Term of patent 7 years.

To all whom it may concern:

Be it known that I, FREDERIC L. FELTON, a citizen of the United States, residing at Boston, Suffolk county, Massachusetts, have invented and produced a new and original Design for a Combined Calendar and Paper-Weight, of which the following is a specification, reference being had to the accompanying drawings, forming part thereof.

10 Figure 1 represents, in perspective, my newly-designed combined calendar and paper-weight, and Fig. 2 a rear-side view thereof.

15 My design for a combined calendar and paper-weight consists, essentially, of a barrel, *a*, turned over, with its bilge placed upon a rest or base, *b*. At one side of this barrel is a slit, *c*, from which is shown as protruding the end of a strip, *d*, on which are printed the days of the week, the months, and figures for the days 20 of the month. About the barrel are painted or otherwise designed hoops *e*, and the body of the barrel at front and top will preferably be painted and striped to represent staves 33.

25 The barrel, with its base, being made of iron or other metal, is sufficiently heavy to be used as a paper-weight.

I am aware that it is old to construct an ink-stand in the form of a barrel resting upon a block or base, and having at its bung-hole a tubular extension to form the mouth of the ink-stand; but my design differs from this in that it is for use as a paper-weight, has a calendar attached, and dispenses with the mouth-piece of the inkstand. 30

I claim—

The design for a combined calendar and paper-weight herein shown and described, consisting of an imitation barrel turned over, with its bilge placed upon a base, and having a slit, *c*, and a strip, *d*, upon which strip are printed the 40 days of the week, the months, and figures for the days of the month. 35

In testimony whereof I have signed my name to this specification in the presence of two subscribing witnesses.

FREDERIC L. FELTON.

Witnesses:

G. W. GREGORY,
N. E. C. WHITNEY.
